UNITED STATES PATENT OFFICE.

SYLVESTER CHARLES, OF SAN JOSE, CALIFORNIA.

TWO-CYCLE INTERNAL-COMBUSTION ENGINE.

1,215,483.

Specification of Letters Patent.

Patented Feb. 13, 1917.

Application filed October 7, 1915. Serial No. 54,623.

To all whom it may concern:

Be it known that I, SYLVESTER CHARLES, a citizen of the United States, residing at San Jose, in the county of Santa Clara and State of California, have invented certain new and useful Improvements in Two-Cycle Internal-Combustion Engines; and I do declare the following to be a full, clear, and exact description of the invention, such as will enable others skilled in the art to which it app pertains to make and use the same.

My invention relates to improvements in internal combustion engines and primarily to those of the two-cycle type.

The object of the invention is to improve upon the general construction of engines of the class specified to such an extent as to provide a machine which, although being simple and comparatively inexpensive, will possess a number of advantageous characteristics.

With this general object in view, the invention resides in certain novel features of construction and in the unique combinations of parts to be hereinafter fully described and claimed, the descriptive matter being supplemented by the accompanying drawings wherein:

Figure 1 is a vertical transverse section of an engine constructed in accordance with my invention showing the positions of parts at the completion of a working stroke thereof;

Fig. 2 is a vertical longitudinal section disclosing the relative location of parts immediately preceding ignition; and

Fig. 3 is an end view of the cylinder with the head thereof removed.

In these drawings which constitute a part of this application similar reference characters designate corresponding parts throughout the several views, the numeral 1 having reference to the cylinder of the engine which is shown as disposed vertically and supported by an appropriate type of crank case 2 in which is rotatably mounted a power shaft 3 having a pair of cranks 4 extending to one side of its center and an additional crank 5 projecting approximately in a diametrically opposite direction but slightly offset in order that all cranks may not be positioned on dead center at the same time.

The upper end of the cylinder 1 is provided with an annular groove 6 which registers with a similar groove 7 in a cylinder

head 8, said head having in its edge portion 55 an annular fuel heating chamber 9 preferably enlarged at an appropriate point as disclosed at 10, at which point the fuel supply tube 11 from the carburetor (not shown) discharges into said chamber. The usual type of spring 60 closed intake valve 12 normally obstructs communication between the chamber 10 and the tube 11, but obviously this valve might well be of a mechanically operated type.

Leading from the annular chamber 9 into 65 the fuel heating channel formed by the registering grooves 6 and 7, is an annular series of ports 13, while leading from said channel into the cylinder 1 immediately beneath the head thereof, is an annular series of intake 70 ports 14, said ports being not only in communication with the interior of the cylinder, but being in constant unobstructed communication with an annular series of upright bypasses 15 which deliver into said cylinder at 75 points spaced beneath the ports 14. This arrangement of parts is essential for a reason to be obvious as the description proceeds.

Surrounding the lower end of the cylinder 1 and preferably cast integrally therewith, is 80 an exhaust manifold 16 into which an annular series of exhaust ports 17 discharges from the cylinder. Preferably, a fuel supply pipe 18 which leads from the carburetor or mixing valve to the tube 11 is disposed in the 85 manifold 16 directly opposite the ports 17. By this means, the fuel passing through the aforesaid pipe will be effectively heated and rendered highly volatile. It is to be observed that by relating the pipe 18 with the 90 ports 17 in the manner specified, said pipe will be heated uniformly throughout its length thus increasing its efficiency.

Slidably mounted in the cylinder 1 is a tubular piston 19 having a head 20 spaced 95 slightly below its upper end, while immediately below said head the piston is provided with an annular series of intake ports 21 adapted to register at predetermined intervals with the bypasses 15. A similar series 100 of exhaust ports 22 is formed near the lower end of the piston 19 for intermittent registration with the ports 17 before described. The lower end of the piston 19 is provided with a pair of diametrically opposed trunnions 23 from which a pair of connecting rods 24 lead to the cranks 4, while leading from the opposed crank 5 is an additional

connecting rod 25 whose upper end carries a common type of piston 26 disposed slidably in the tubular piston 19. By so connecting the two pistons 19 and 26 with the cranks 4 and 5, said pistons will reciprocate simultaneously but in opposite directions whereby they may receive and compress therebetween the explosive fuel mixture. The admission of the fuel is effected as follows:

- 10 The engine is cranked in the usual manner, thus causing the downward stroke of the piston 19 to create a partial vacuum in the cylinder 1 above the piston head 20, such vacuum now causing fuel to be drawn from the tube 11 into the annular chamber 9, and from this chamber through the ports 13 and 14 into the upper end of the cylinder. When this takes place, the two piston heads are spaced in close proximity, but upon further rotation of the crank shaft, the piston 19 moves upwardly while 26 travels downwardly, the upward movement of said piston 19 causing its head 20 to compress the charge of explosive mixture against the cylinder head 8. By the time the charge has been sufficiently compressed, the intake ports 21 align with the lower ends of the by-passes 15; whereupon the charge is forced into the tubular piston 19 between its head and the head of the piston 26. As cranking is continued, the heads of the two pistons move toward each other and compress the charge therebetween, upon termination of which action, one of the intake ports 21 is positioned directly opposite the spark plug or the like 27 carried by the cylinder 1. The timing mechanism (not shown) now causes the plug to create a spark thereby igniting the charge of compressed fuel between the two piston heads with the result that such heads are driven from each other and the engine travels under its own power.
- 45 The exhaust ports 22 align with the ports 17 at the end of each working stroke of the engine substantially at the same time at which the ports 21 register with the by-passes 15. By so doing, the incoming charge forces the burnt gas from the interior of the engine in the manner well known to those familiar with the operation of two-cycle engines. The scavenging of the cylinder, however, and the filling thereof with a fresh charge of fuel, is facilitated by the specific arrangement of the ports 21 and 22, since this relation causes the incoming charge to be quickly distributed in the upper end of the piston 19, thereby forcing the burnt gases bodily downward and expelling them through the ports 22. After the new charge has been admitted, the momentum imparted to the usual fly wheel 28 causes the engine to remain in motion until such charge is again compressed and fired.

It is to be observed that the spark plug 27 is only exposed when the charge of mixture is to be ignited, this being a rather salient feature, since by this provision, the plug is prevented from carbonizing as often occurs when it is exposed at all times to the explosions within the cylinder.

Due to the relation of the fuel supply pipe 18 and the exhaust ports 17 and due also to the chamber 9 and channel formed by grooves 6 and 7, crude oil may be effectively used as a fuel since it will be rendered highly volatile, but in view of the fact that considerable residue will settle from such oil upon the piston head 20, it is highly expedient to provide means whereby such residue may be blown out when necessary. To this end, the central portion of the cylinder head 8 is formed with a cavity 29 whose bottom is equipped with a valve seat 30, while its top is formed with a plurality of outlet ports 31 and with a central opening with which a guide 32 is threaded. The guide 32 receives therein the upright stem 33 of an appropriate valve 34 normally bearing on the seat 30 and held in this position against compression in the cylinder by a coiled spring 35 of suitable strength. Under normal conditions, the guide 32 is held against movement to retain the valve 34 seated, by a lock nut 36, but when residue from the fuel accumulates upon the piston head 20, loosening of the nut 36 will allow the guide 32 to be so rotated as to relieve tension on the spring 35. This operation will allow air compressed by the upward movement of the piston 19 to be blown from the cylinder, such air carrying with it the residue and thus effecting the cleaning operation in a reliable manner. Obviously, the engine must be cranked by hand to force air from the upper end of the cylinder in the manner just set forth, or if desired, the valve 34 and the guide 32 may be removed thus giving access into the cylinder for cleaning by any other preferred method.

An engine constructed as above described will possess a number of advantageous characteristics among the most important of which are the following:

Excessive lateral thrust upon the bearings of the power shaft is prevented since the impulse of the explosions in the engine is equalized upon said shaft; vibration is practically eliminated; the incoming gases are more readily admitted and the burnt gases more easily discharged than with a number of other types of engines; the spark plug 27 is normally protected against carbon and the like, and the fuel is rendered volatile to a greater degree than by other devices now used for this purpose.

In the drawings, certain specific details of construction have been shown for accom-

plishing probably the best results, but obviously numerous changes may be made within the scope of the appended claims.

I claim:

- 5 1. In an internal combustion engine, a pair of oppositely moving pistons between which the explosive mixture is compressed and fired, a cylinder in which said pistons are disposed, said cylinder having an open end disposed in a plane at right angles to its axis and formed with an annular groove, said cylinder also having a number of circumferentially spaced intake ports leading from said groove, and a cylinder head secured in contact with said end of the cylinder and having an annular groove registering with the aforesaid groove and forming therewith a fuel heating channel, said head also having an annular fuel heating reservoir with a fuel inlet, and a plurality of circumferentially spaced ports leading from said reservoir into said channel.
- 10 2. In an internal combustion engine, a cylinder having an open end disposed in a plane at right angles to its axis, said end being formed with an annular groove, intake ports leading from said groove into the cylinder, unobstructed by-passes leading from said ports and discharging into the cylinder at points spaced therefrom, a cylinder head secured in contact with the aforesaid end of the cylinder and having an annular groove registering with the aforesaid groove and forming therewith a fuel heating channel, said head also having an annular fuel heating reservoir with a valved inlet, and a plurality of circumferentially spaced ports leading from said reservoir into

the aforesaid channel, the body of the cylinder being provided with a series of circumferentially spaced exhaust ports spaced from the by-passes, a tubular piston slidable in the cylinder and having a closed inner end formed with a series of circumferentially spaced intake ports for registration with the aforesaid by-passes, said piston also having an annular series of spaced exhaust ports for registration with the exhaust ports in the cylinder, a second piston movable in the tubular piston, a crank shaft having opposed cranks, and connecting rods connecting said opposed cranks with the two pistons.

3. In an internal combustion engine, a cylinder, a tubular piston therein adapted to draw explosive mixture into said cylinder and force it into its own interior, a second piston operable in said tubular piston for compressing the explosive mixture therein, a head for said cylinder in the form of a shell having a perforated outer side formed with a central opening and having a valve seat in its inner side communicating with the interior of the cylinder, a bushing threaded in the aforesaid opening, an outwardly opening valve normally closing the aforesaid valve seat and having a stem slideable in the bushing, and a coil spring interposed between the latter and said valve, substantially as and for the purpose specified.

In testimony whereof I have hereunto set my hand in presence of two subscribing witnesses.

SYLVESTER CHARLES.
